UNITED STATES PATENT OFFICE.

JOHN WAHLBERG, OF NEW YORK, N. Y.

PHONOGRAPH.

Application filed May 17, 1922. Serial No. 561,586.

My present invention relates to the improvement of phonographs and particularly to the stopping and starting thereof.

The general objects of the invention are 5 to provide simple and practical means for automatically stopping or otherwise suitably controlling the mechanism at the end of playing a record and to provide such mechanism in a form readily applicable to the ordinary 10 phonograph, or to the special automatic record-changing phonograph of the character covered in my Patent #1,390,404.

The foregoing and other objects are attained in my invention by means of cert- 15 tain novel features of construction, combina- tions and relations of parts, as will be clear from the following specification.

In the drawings accompanying and forming part of this specification I have illus- 20 trated certain preferred embodiments of the invention, but wish it understood that such illustrations are primarily intended for purposes of disclosure, and that, therefore, the structure may be modified in various re- 25 spects without departing from the broad spirit and scope of the invention as herein- after defined and claimed.

Figure 1 in the drawings referred to is a 30 broken plan view of one form of the invention as applied to an automatic phonograph like that disclosed in my patent. In this view the guide pin at the center of the turn-table is shown in section to disclose the manner in which the trip cam is cut in 35 the side of the pin so as not to interfere with the placing or removal of the records.

Figure 2 is a cross sectional view of the 40 record as taken on substantially the plane of line 2-2 of Figure 1, looking at the end of the tone arm and showing the point of the trip lever as having been carried by the travel of the sound-box into engagement with the actuating cam on the guide pin.

Figure 3 is a left hand side elevation of 45 the parts shown in Figure 1.

Figure 4 is a broken side elevation, partly 50 in section, showing a form of the invention adapted to a type of phonograph in which the tone arm is pivoted at its base end, instead of having a swiveled goose-neck structure, as in the form first disclosed.

Figure 5 is a broken plan and part sec- 55 tional view of this modified form of the invention.

Figures 6 and 7 are broken plan and end

views, similar to Figures 1 and 2 respectively, showing a simplified form of the invention applicable to an ordinary phonograph, and in which the separate lifting and trip 60 levers of the automatic phonograph are replaced by a single combined lifting and trip lever.

Figure 8 is a left hand side elevation of this latter simplified form of automatic stopping and starting attachment, with the parts shown as they appear just before the latch is tripped to stop the machine and lift the reproducer clear of the record.

Figure 9 is a similar view showing the 70 parts tripped with the brake applied to the turn-table and the sound-box lifted clear of the record.

Figure 10 is a right hand side elevation of 75 the mechanism, with the parts as they appear at the moment of tripping.

In the first three figures I have disclosed sufficient of the mechanism of my automatic phonograph to illustrate the application of the present invention thereto. In these views 80 15 designates the turn-table supporting the record R and 16 designates a sound-box of well known construction carrying a suitable stylus 17 for engagement with the record and pivoted at 18 to a swinging tone arm 19. A portion of the indexing mechanism by which the turn-table is intermittently lowered step by step is indicated at 20 and the arcuate track by which this mechanism is controlled is shown at 21, said track being 85 engaged by a roller 22 on the lower end of a bell crank lever 23, pivoted at 24 on a support or base plate 25 secured to the tone arm. As in the patent, this bell crank lever is shown as carrying a restoring lever 26 having a roller 27 for engagement with a restoring cam 28, the upper end of said lever being positioned to engage a slide 29 which is connected with the swinging power lever 30. This power lever is pivoted at 31 in an arched bracket 32 and is 90 acted upon by a spring 33.

The trip lever 34 for restraining and holding the power lever normally inoperative is shown pivoted on the base 25 at 35 and as having a hook or catch 36 at its outer end for engagement with a tooth 37 on the lower end of the power lever.

The tone arm lifting lever 38 is pivoted at 39 on the supporting base and extends at its rearward end beneath the power lever so as to be actuated thereby when the power lever

is tripped. In like fashion the forward arm of the bell crank lever extends beneath the power lever, carrying a projection 40 beneath the lower end of the power lever so 5 that it also will be actuated on the rearward swing of the power lever.

The parts thus far described operate as in the patent; that is, when the trip lever is actuated to release the spring impelled power 10 lever, said power lever will depress the outer end of the lifting lever to raise the reproducer clear of the record and will rock the bell crank lever so as to cause it to actuate the turn-table indexing mechanism.

15 In the form of the automatic machine disclosed in my patent the impulse for actuating the trip lever is supplied by dropping the sound-box onto the trip lever, either automatically at the end of a record, by causing 20 the stylus to drop into a tripping groove at the end of the sound groove or manually, at will, by arbitrarily operating the indexing mechanism to lower the turn-table, and hence impart a falling movement to the reproducer.

25 In the present invention the trip lever is in effect controlled by the sound-box or reproducer, but the tripping impulse is supplied by means independent of the sound-box and consists of a cam or trip shoulder 30 on the guide post at the center of the turn-table, with which the trip lever is engaged by the inward travel of the reproducer over the sound record.

In order that this cam shall not interfere 35 with the placing or removal of the records, I have shown the same as sunk in the side of the guide post or pin 41 and in the form of a downwardly inclined and undercut wall 42 at the upper side of a radial slot 43 cut in 40 the side of the post. This slot is of sufficient length and the shoulder is of sufficient inclination to effect a positive tripping impulse. To quickly release the trip lever after the tripping impulse the slot in the side 45 of the post is extended longitudinally at the lower end of the trip shoulder to form a recess 44 (Figures 3 and 10) which will free the lever of the cam shoulder.

The engagement of the trip lever with the 50 cam is effected through a finger designed to readily enter the slot in the side of the rotating spindle and shown in the form of a lever element 45 pivoted at 46 on the body of the trip lever, and having a laterally extended 55 tooth 47 with its entering edge cut substantially radially of the spindle, as shown at 48 in Figure 1, and inclined upwardly as shown at 49 in Figure 2, to match the incline of the undercut shoulder. This cam engaging lever 60 is shown as yieldingly pressed toward the cam by a spring 50, and the extent of projection of such lever is shown as governed by a screw 51 in the tail end of the lever engaging the body of the trip lever.

65 In the operation of the phonograph the

tone arm swings inward and the finger at the end of the tripping lever is thereby carried inward or toward the center of the turn-table. It will be seen that if the sound groove in the record extends far enough inward the tripping finger will be carried thereby into operative engagement with the trip cam and for this special purpose the records may all be made with the sound groove terminating at a point near enough 70 the center to thus actuate the parts. If desired, however, special means may be provided for automatically swinging the tone arm further inward, after the end of the sound groove has been reached. Thus I have 75 shown in Figures 1 and 2 a smooth incline or slope 52 in the face of the record at the inner end of the sound groove, down which the stylus will slide and so carry the point of the trip lever into engagement with the 80 cam; and in Figure 6 I have shown the record as having a quick spiral groove 53 leading from the inner end of the sound groove for effecting the same purpose. By 85 adjusting the set screw it will be seen that 90 the trip finger can be positioned to properly cooperate with the cam no matter which one of these methods is used.

Operation.

95

In the playing of a record on the turn-table, the reproducer, and hence the tone arm, is swung inwardly under the guidance of the sound groove until finally the lug or finger at the point of the trip lever is carried inward far enough to engage beneath the upper end of the inclined cam shoulder on the guide post. As above outlined the final movement necessary to effect this engagement may be produced, for example, either by a continuation of the sound groove, a "leading in" incline such as shown in Figure 2, or a quick spiral such as shown in Figure 6. The resilient character of the tripping finger enables it to yield, if upon first contact with the record post it does not directly engage beneath the cam shoulder and the undercut construction of the cam shoulder with the matched upward incline of the finger causes the two to interlock as soon as a positive engagement is effected. This relation is indicated particularly in Figures 3 and 8. Under the action of this cam the inner end of the trip lever is depressed and the outer end is rocked upwardly to release the hook from holding engagement with the power lever 30. The power lever thus released, in the first form of the invention disclosed, as more fully illustrated in my Patent #1,390,404, rides over the outer end of the lifting lever 38, rocking its inner end upwardly so as to lift the reproducer off the record and also rocks the forward arm of the bell crank lever 23 downwardly, as shown in the dotted lines 130

in Figure 3, so as to cause the dependent arm of such lever, by engagement with the track 21, to rock the indexing lever 54, which carries this track, outwardly and thus set into action the indexing mechanism for lowering the turn-table and setting the other mechanism into operation for effecting the tone arm swinging movements and record-changing or other actions.

10 In the automatic machine of my patent, after the last record is played or in some instances, between the playing of successive records, the brake is automatically applied to stop the phonograph, so it will be realized that the novel mechanism herein disclosed and thus far described is effective both for raising the reproducer off the record and for stopping the machine.

15 The longitudinal recess in the guide post at the end of the trip cam serves to release the trip lever practically the instant it has accomplished its work so that the tone arm is immediately free to swing outwardly and carry the reproducer off to one side of the record as soon as it is lifted off the record by the lifting lever.

20 If desired, the mechanism may be tripped at any time during the playing of a record by simply depressing the trip finger by hand, it being noted that this trip finger stands out so that it can be easily reached for this operation without disturbing the sound-box or other parts.

35 *Independent operation of lifting lever.*

25 The lifting lever may be operated arbitrarily at any time independent of the automatic mechanism described, by means of a push button 55 similar to the one disclosed in my automatic phonograph patent, said push button being shown as guided for vertical movement in a bracket 56 and carrying an arm 57 overstanding the outer end of the lifting lever. On depressing this button it will be seen that the lifting lever can be actuated when desired to lift the stylus clear of the record, and that by means of this same button the tone arm may be swung in one direction or the other either to skip portions of a record, to bring the tripping cam into action, or to carry the tone arm off to the side of the record.

30 In Figures 4 and 5 I have disclosed the invention as applied to a phonograph of the type in which the lifting movement of the reproducer is provided for by pivoting the tone arm at its base on a horizontal pivot or pivots 58. In view of this vertical tilting of the tone arm it is impractical to support the tripping and lifting mechanism directly thereon so a separate support is provided for this purpose, shown in the illustration as a ring 59 encircling the throat 60 of the horn or amplifying chamber, carrying upstanding posts 61, 62 standing at

opposite sides of the tone arm and to one of which is attached the bracket 63 which forms the mounting or support for the lifting and trip levers 34 and 38 respectively. To overcome friction and prevent the bracket 70 supporting ring from interfering with the free swinging of the tone arm, the ring is shown as floated between ball bearings 64 and 65 which can be adjusted for wear by means of a confining ring 66 screwed onto the upper end of the throat piece. To afford a fairly close fit between the tone arm and the lever supporting bracket the arms 61, 62 which constitute in effect a fork receiving the body of the tone arm may be provided with pads or cushions 67, which serve the added purpose of preventing chattering between these parts.

35 *Operation of the structure of Figures 4 and 5.*

40 The operation of this form of the invention is similar to the one first described in that as the tone arm swings inward the lever supporting bracket will be carried inwardly thereby until finally the finger of the tripping lever will be brought into engagement with the cam of the guide post and be actuated thereby; whereupon, the power lever will be released and will operate on the lifting lever to lift the reproducer off the record. In this instance the tone arm pivots bodily about the center 58, as indicated in dash lines in Figure 4, the lifting movement being insufficient to practically effect the engagement between the tone arm and the supporting bracket to which it is loosely connected.

45 *Combined trip and lifting lever.*

40 In the form of the invention disclosed in Figures 6 to 10 I have shown how the functions of the tripping lever and reproducer lifting lever may be effected by a single lever 68 pivoted on a bracket positioned or carried by the tone arm and generally similar to the trip lever previously described, corresponding reference characters being used where possible to indicate this similarity. This lever, however, differs from the first trip lever in that it carries a lifting extension 69 positioned beneath the swiveled neck of the sound-box and in that it is engaged at its rearward end by an actuating cam shoulder on the power member. This power member or lever which is here designated 70 also is of different construction in that it is pivoted at its lower end on the tone arm bracket at 71 and is provided at its upper end with a projecting handle 72 by which it can be manipulated for resetting purposes and for swinging the tone arm.

45 An interlocking connection is provided between the power lever and the end of the combined lifting and trip lever by means of a slot or recess 73 in the forward edge of the

power lever designed to receive the end of the trip lever. This slot is shown as shaped to provide a hook or guard 74 overstanding the upper edge of the lifting and trip lever, and inside of that, a point or shoulder 75 to ride over an inclined shoulder 76 on the end of the trip lever and below that, substantially beneath the overstanding hook, a tooth 77 for engagement by a lug or tooth 78 at the lower edge of the trip lever.

The power is supplied in this instance by a spiral spring 79 connected between the forward edge of the power lever and the lower edge of the trip and lifting lever.

15 *Operation of structure of Figures 6 to 10.*

With the parts set as in Figure 8, the lifting projection of the trip lever is free of the reproducer, which operates as usual. In 20 the swing of the tone arm toward the center of the record the point of the trip lever is finally brought into engagement with the actuating cam on the guide post which operates as shown in Figure 10 to depress the 25 forward end of such lever so as to release the rearward end of the same from holding engagement with the tooth of the power lever. At approximately the time of such release the point of the trip lever is ready to 30 pass into the recess 44 at the end of the cam shoulder and said lever is therefore free to be elevated for the purpose of lifting the sound-box. The power lever therefore becomes effective, substantially at the moment 35 of its release, to depress the outer end of the lifting and trip lever, which it does by swinging forwardly under the power of the spring. In its forward movement the shoulder 75 of the power lever rides up the 40 incline 76 on the end of the lifting and trip lever, forcing the same downward and so elevating the sound-box as in Figure 9. This movement may be assisted somewhat by the point of the hook 74 riding over the upper 45 edge of the lever 68 and at the end of such movement the point 75 of the power lever overstands a flat shoulder 80 at the upper end of the incline 76, thereby interlocking the two levers on a line with the pivot 71 50 so as to automatically positively lock the reproducer in its lifted relation. It will also be observed that when the two levers are thus interlocked they cannot be released by pressure on the tripping point of the lever 68.

55 With the reproducer thus locked in elevated position the tone arm can be safely swung one way or the other without danger of accidentally dropping the stylus down on the record, such swinging movements usually 60 being effected by means of the projecting handle 72. And when it is desired to lower the sound-box onto any portion of the same or a new record this can be done from the handle 72 by swinging the tone arm to the 65 desired location and then forcing the handle

outwardly to the position shown in Figure 8, in which action the inclined shoulder 81 at the back of the tooth on the power lever rides under the inclined shoulder 82 in front of the tooth on the lever 68 so as to lift the 70 outer end of the latter and thus lower the reproducer onto the record. In this latched relation it will be seen that the point of the hook 74 on the power lever overstands an incline 83 at the forward end of the interlocking shoulder 80 on lever 68 so as to operate as a guard limiting the releasing movement of such lever and preventing any possibility of disengagement of such levers. This feature is particularly important when 75 the lever is tripped by hand as by pressure on the handle or tripping extension 84 provided for such arbitrary control. The rearward or resetting stroke of the power lever may be limited by a suitable stop 85 carried 80 by the supporting bracket and located to the 85 rear of the lever.

To provide a proper relation between the sound-box and the lifting portion of lever 68 I have shown the part 69 as pivotally 90 secured at 86 to the body of the lever and as held in adjusted relation by a set screw 87 extending through a slot 88, the tripping button 84 at the end of the lever forming a convenient handle for effecting this ad- 95 justment.

Brake setting and releasing mechanism.

In the construction disclosed in Figures 6 to 10 the brake is automatically applied to 100 stop the machine when the power lever is tripped and is automatically released to again start the machine when the tone arm is swung outwardly beyond a predetermined point. 105

The brake mechanism includes a lever 89 pivoted at 90 on a suitable base 91, said lever carrying a brake block 92 for engagement with the rim of the turn-table and having a shoulder 93 for engagement by the end of 110 a lever 94 pivoted at 95 on base plate 91, a spring 96 serving to draw the two levers together and the latch lever 94 carrying an arcuate track 97 for engagement by a tappet 98 on the lower end of the power lever. This 115 tappet is shown as pivotally supported at 99 and as normally rocked downwardly into position to engage the arcuate track by a spring 100 (Figure 8). This spring mounting of the tappet permits it to yield and snap in front of the track when the power lever is reset or restored from the tripped relation indicated in Figure 9 to the position shown in Figure 8. 120

The brake is released to start the machine 125 by a lug 101 which may be a dependent portion of the supporting bracket on the tone arm and which is positioned to engage a rearwardly or outwardly projected portion 102 of the brake lever. These parts are so 130

related that an engagement between the two will be effected only when the tone arm is swung to an extreme outer position clear of the record on the turn-table and the projection 102 may be of sufficient extent and inclined so as to operate as a frictional stop for yieldingly retaining the tone arm in its outwardly swung position.

10 *Operation of brake setting and releasing mechanism.*

When the power lever is released by operation of the combined tripping and lifting lever the tappet at the lower end of the same 15 engages the arcuate track of the brake restraining latch, tripping the latch and causing the brake to be applied practically simultaneously with the lifting of the reproducer off the record. The arcuate track construction 20 enables this operation to take place at any point in the swing of the tone arm. The reproducer being thus clear of the record, the tone arm is free to be swung one way or the other and can, if desired, be 25 swung only far enough to one side to permit changing of the record. After the change is made the tone arm may be swung outward the slight further distance necessary to release the brake and reset the brake-holding latch; whereupon, with the turn-table 30 in motion, the tone arm may be swung inward to carry the reproducer over the beginning or any selected portion of the record and then be gradually and easily lowered into engagement with the same by returning the power lever back to its normal inactive position, restrained by the combined trip and lifting lever 68. (Figure 8).

What I claim is:

40 1. In a phonograph, a turn-table having a record guiding pin provided with a cam sunk in the side thereof, a swinging tone arm, a pivoted trip lever adapted to be carried by said tone arm into operative engagement with said cam at the end of the playing of a record on the turn-table and means for controlling a function of the phonograph under control of said trip lever.

50 2. In a phonograph, a rotating record guiding pin recessed and provided with an inclined shoulder in the side thereof and a trip member having a projection to enter said recess and be actuated by the inclined shoulder thereof.

3. The structure of claim 2 in which the projection is yieldable.

4. The structure of claim 2 in which the projection is pivoted on the trip member and has a set screw for accurately positioning the same on the trip member.

5. The structure of claim 2 in which the projection is both yieldable and adjustable on the trip lever.

65 6. The structure of claim 2 in which the

trip member is associated with a swinging tone arm and is positioned thereby.

7. The structure of claim 2 in which a relief is provided at the end of the inclined shoulder to release the projection.

70 8. In a phonograph, a rotating turn-table having a record guiding post, a brake for the turn-table, a controller for said brake having an arcuate track, a reproducer for engagement with a record on the turn-table, an actuating mechanism for the controller, said actuating mechanism being positioned by the reproducer and having a part for engagement with the arcuate track and a finger projecting toward the record guiding post and a cam on the record guiding post for operatively engaging the finger aforesaid to cause said mechanism to actuate the brake controller by engagement with the arcuate track.

75 9. The structure of claim 8 with means for tripping the actuating mechanism independently of the cam and at any point in the travel of the reproducer over the record surface.

80 10. In combination with the structure of claim 8, a record provided with means at the end of the sound groove therein for shifting the reproducer to carry the finger into tripping relation with the cam.

85 11. The structure of claim 8 in which the post is provided at the end of the cam shoulder with a recess for suddenly releasing the tripping finger.

90 12. The structure of claim 8 in which the cam is in the form of an inclined wall constituting one side of a peripheral slot formed in the side of the post.

95 13. In a phonograph, a turn-table, a record guiding post at the center thereof and over which the records are freely engageable, said post having a peripheral slot in one side of the same and phonograph control mechanism having a part to enter said slot in the side of the record guiding post, with means for effecting engagement of said part in said slot at the end of a record on the turn-table and irrespective of the length of the sound groove in the record.

100 14. The structure of claim 13 in which said control mechanism is traversed across the record by a reproducer supported for engagement with a record on the turn-table.

105 15. In a phonograph, a rotating turn-table, a record guiding post at the center thereof, control mechanism for the phonograph and non-protruding means on the record guiding post for actuating said control mechanism adapted to permit unobstructed engagement of the records over the guide post.

110 16. In a phonograph, a record supporting turn-table, a rotating record guiding post at the center of the same, a reproducer for engagement with a record on the turn-

table, a reproducer lifting device, actuating means for the same carried by the record guiding post and a record on the turn-table provided with means at the end of the record groove therein for producing operative engagement of said actuating means with the reproducer lifting device.

17. In a phonograph, a rotating turn-table, a reproducer for engagement with a record on said turn-table, reproducer lifting means positioned by the reproducer, a record guiding pin operating in conjunction with the turn-table and rotating therewith for actuating said reproducer lifting mechanism, phonograph stop mechanism and means for initiating operation of the same also actuated by said record guiding pin.

18. In a phonograph, a turn-table having a rotating record guiding post provided with a cam in the side thereof, sunk below the record guiding surface of the post so as not to interfere with the placement and removal of records on the turn-table and turn-table controlling and reproducer lifting mechanism having means for actuation by the cam on the record guiding post.

19. In combination with the structure of claim 18, a record on the turn-table provided with means at the end of the record groove therein for shifting the reproducer toward the guide post, the turn-table control and reproducer lifting mechanism having a part positioned by the reproducer and adapted to be shifted thereby into engagement with the actuating means on the guide post.

20. In a phonograph, a turn-table, a spring actuated brake therefor, a latch for restraining said brake provided with an arcuate track, a spring actuated lever having a part for engagement with said track, a trip lever for restraining said spring actuated lever, a reproducer for engagement with a record on the turn-table, connecting means for shifting said spring actuated and trip levers in accordance with the travel of the reproducer over the record and means at the center of the turn-table for actuating said trip lever to free the spring pressed lever.

21. The structure of claim 20 with independent means for arbitrarily actuating the trip lever irrespective of the travel of the same across a record on the turn-table.

22. The structure of claim 20 in which said actuating means includes a cam shoulder formed in the side of a record guiding spindle.

23. In a phonograph, a swinging tone arm, a spring actuated controller for the phonograph, a latch for restraining said controller and means positioned by the tone arm for releasing the latch and for resetting the controller.

24. In a phonograph, a swinging tone arm, a spring actuated controller for the phonograph, a latch for restraining said

controller and means positioned by the tone arm for releasing the latch and for resetting the controller, including a power device for cooperation with the latch at any point in the travel of the tone arm and a shoulder for engagement with a projecting portion of the controller at a point toward one end of the swinging movement of the tone arm.

25. In a phonograph, a trip lever, a lever having a latching engagement with said trip lever, means for swinging the latch lever in opposite directions and including cam connections between the two levers for controlling the movement of the trip lever during the swinging motion of the latch lever.

26. In a phonograph, a trip lever, a lever having a latching engagement with said trip lever, a handle at the upper end of said latching lever, a shoulder at the lower end of the latch lever and means for controlling a function of the phonograph having a part standing in the path of said shoulder.

27. In a phonograph, a rotating turn-table, a spring actuated brake therefor, a controller for said brake having an arcuate track, a reproducer for engagement with a record on the turn-table, a power member positioned by said reproducer and adapted to operatively engage the arcuate track, a restraining device for said power member and means carried by the turn-table including a record guiding stem for operating said restraining device.

28. In a phonograph, a rotating turn-table, a reproducer for engagement with a record on said turn-table, reproducer lifting means positioned by the reproducer and means connected with the turn-table and rotating therewith for actuating said reproducer lifting mechanism and including a record guiding pin at the center of the turn-table having a reduced or recessed portion and the reproducer lifting means including a part for cooperation therewith.

29. In a phonograph, a reproducer, a power member positioned thereby and a restraining element for said power member having an interlocking connection with the same whereby upon actuation of the restraining element the power member will hold the same against further movement.

30. In a phonograph, a turn-table having a record guiding pin provided with a cam sunk in the side thereof, a swinging tone arm, a trip adapted to be carried by said tone arm into operative engagement with said cam, means for controlling a function of the phonograph under control of the said trip and automatic leading-in means for the reproducer for positively effecting operative engagement of the trip with the cam at the end of the playing of a record on the turn-table.

31. Automatic control for phonographs comprising in combination with means for

- controlling a function of the phonograph and actuating means therefor positioned by the reproducer in its travel over the record and a restoring device for resetting the control means operative in the outward swinging movement of the reproducer and having frictional engagement with the control means to restrain the reproducer in its outward position.
32. In a phonograph, a turn-table having a record guiding pin with a cam sunk in the side thereof, a brake for the turn-table and a latch for said brake, a power member for actuating said latch, a trip for restraining the power member and arranged to be carried by the movement of the reproducer into operative engagement with the cam on the guide pin and a resetting projection arranged to be carried by the movement of the reproducer into restoring engagement with the mechanism of the brake.
33. In a phonograph, a turn-table having a record guiding pin over which the record is passed to center the same, said pin having a cam sunk in one side of the same, a swinging tone arm, a trip adapted to be carried by said tone arm into operative engagement with said cam, means for controlling a function of the phonograph, said means being controlled by the trip and the trip having a yieldable portion enabling the trip to yield under the propelling influence of the tone arm until it makes engagement with the cam in the centering pin.

In witness whereof, I have hereunto set my hand this 2nd day of May, 1922.

JOHN WAHLBERG.
